UNITED STATES PATENT OFFICE.

JACOB A. BOOS, OF MOUNT VERNON, NEW YORK.

ERASER-HOLDER FOR PENCILS.

1,237,013.

Specification of Letters Patent. Patented Aug. 14, 1917.

Application filed February 28, 1917. Serial No. 151,417.

To all whom it may concern:

Be it known that I, JACOB A. BOOS, a citizen of the United States, and a resident of Mount Vernon, in the county of Westchester 5 and State of New York, have invented a new and Improved Eraser-Holder for Pencils, of which the following is a full, clear, and exact description.

The object of the invention is to provide 10 a new and improved eraser holder for pencils and similar articles and arranged to provide an eraser of sufficient length to ordinarily last until the pencil is used up, and to permit of removing a portion of the 15 holder whenever the free outer end of the eraser has become worn down to the holder with a view to keep a portion of the eraser extending beyond the outer end of the holder.

20 In order to produce the desired result use is made of a ferrule adapted to hold an eraser and adapted to be fastened at one end to a pencil or a similar article, the ferrule being weakened circumferentially at a point 25 between the ends to provide a detachable portion.

A practical embodiment of the invention is represented in the accompanying drawings forming a part of this specification, in 30 which similar characters of reference indicate corresponding parts in all the views.

Figure 1 is an enlarged elevation of one side of the eraser holder as applied to the butt end of a lead pencil;

35 Fig. 2 is a similar view of the other side of the same;

Fig. 3 is a perspective view of the same with the outer portion of the holder partly detached;

40 Fig. 4 is an enlarged longitudinal central section of the eraser holder as applied; and

Fig. 5 is a cross section of the same on the line 5—5 of Fig. 4.

The ferrule 10 is adapted to hold an eraser 45 11 preferably of rubber, and one end 12 of the ferrule 10 is fastened onto the butt end of a lead pencil 13 or a similar article in the usual manner, preferably, by providing the end 12 with indentations 14 embedded 50 in the pencil material, as plainly indicated in Fig. 4. The ferrule is provided intermediate its ends with a corrugated portion 15 having the corrugations extending circumferentially, and fitting the correspond-

55 ing portion of the eraser 11 to securely hold the latter in position in the ferrule, as will

be readily understood by reference to Fig. 4. The bottoms of the outermost and innermost corrugations are weakened, preferably by perforations or by spaced slits, indentations 60 or the like, as indicated by 16 and 17. The outer portion 18 of the ferrule extending from the weakening 16 to the outer edge of the ferrule is provided with two parallel weakenings 20 and 21 spaced a short distance apart and extending lengthwise of the ferrule from the outer edge of the ferrule to the weakening 16 at which line the slit extends from the weakening 20 to the weakening 21, as plainly indicated in Fig. 1. 70 By this arrangement the portion between the said weakenings 20, 21 forms a narrow band 22 which can be readily torn off by the user (see Fig. 3) to allow of subsequently peeling or tearing off the remaining 75 portion 18 along the weakening 16. It will be noticed that the eraser 11 extends beyond the outer end of the ferrule when the pencil is new and when the projected portion is gradually worn off close to the outer end 80 of the ferrule (see Fig. 3) then the user readily removes the portions 22 and 18 as above explained. By doing so another portion of the eraser 11 is projected beyond the remaining part of the ferrule. The 85 corrugated portion 15 is provided between the weakenings 16 and 17 with parallel weakening lines 23 and 24 (see Fig. 2) forming a narrow band 25 adapted to be peeled off lengthwise of the ferrule and preferably 90 located diametrically opposite the band 22 formed by the weakening lines 20 and 21 above referred to. Thus if the projecting portion of the eraser 11 has been worn down to the upper edge of the corrugated portion 95 15 then the operator removes the band 25 intermediate the weakenings 23 and 24 to then remove the portion 15 to unobstructedly disclose another portion of the eraser for 100 erasing purposes. The pairs of weakening lines 20, 21 and 23, 24 are preferably made on opposite sides of the ferrule so as not to unduly weaken the general construction of the ferrule. It will be noticed that the corrugations 15 aid in holding the eraser 11 105 in place in the ferrule and the weakening lines 16 and 17 are made at the bottoms of the corrugations so as to present no undesirable raw edges after the portions 18 and 15 are removed as above described.

110 The ferrule shown and described is very simple in construction and can be cheaply

manufactured and applied to lead pencils and similar articles to provide sufficient eraser material for erasing purposes to last until the pencil 13 is used up.

5 Having thus described my invention, I claim as new and desire to secure by Letters Patent:—

1. An eraser holder, comprising a single piece ferrule adapted to hold an eraser and 10 having an outer smooth portion, an intermediate corrugated portion and an inner portion, the intermediate portion being weakened circumferentially in the corrugations adjacent the outer and inner portions, the 15 outer and intermediate portions being weakened lengthwise of the ferrule to permit of first peeling off the outer portion and subsequently the middle portion.

2. An eraser holder, comprising a single- 20 piece ferrule adapted to hold an eraser and having an outer smooth portion, an intermediate portion and an inner portion, the intermediate portion being weakened circumferentially adjacent the outer and inner portions, the outer and intermediate portions 25 having integral bands extending lengthwise of the ferrule and adapted to be peeled off preparatory to peeling off the remainder of the corresponding outer and middle portions.

3. An eraser holder, comprising a single- 30 piece ferrule adapted to hold an eraser and having an outer smooth portion, an intermediate portion and an inner portion, the intermediate portion being weakened circumferentially adjacent the outer and inner portions, the outer and intermediate portions 35 having each two parallel weakened lines ex-

tending lengthwise of the ferrule and forming detachable integral bands adapted to be 40 peeled off prior to peeling off the remainder of the corresponding outer and intermediate portions.

4. An eraser holder, comprising a ferrule adapted to hold an eraser and adapted to 45 be fastened at one end to the butt end of a pencil or similar article, the ferrule having circumferential corrugations spaced from the ends of the ferrule, the bottoms of the first and last corrugations being weakened to 50 provide detachable portions, and weakenings extending lengthwise of the ferrule, one reaching from the outer end of the ferrule to the first circumferential weakening and the other extending from one bottom corrugation 55 to the other and on the side of the ferrule opposite the one on which the first lengthwise weakening is located.

5. An eraser holder, comprising a ferrule adapted to hold an eraser and adapted to 60 be fastened at one end to the butt end of a pencil or similar article, the ferrule having circumferential corrugations spaced from the ends of the ferrule, the bottoms of the first and last corrugations being weakened to 65 provide detachable portions, and weakenings extending lengthwise of the ferrule, one reaching from the outer end of the ferrule to the first circumferential weakening and the other extending from one bottom corrugation 70 to the other and on the side of the ferrule opposite the one on which the first lengthwise weakening is located, each of the said lengthwise weakenings having two parallel portions.

JACOB A. BOOS.
